(57) **CLAIM**

The ornamental design for a cover sheath for a grippable bicycle component, as shown and described.

DESCRIPTION

FIG. 1 is a perspective view of one side of the cover sheath for a grippable bicycle component;

FIG. 2 is a perspective view of the other side of the cover sheath for a grippable bicycle component of FIG. 1;

FIG. 3 is a side view of the cover sheath for a grippable bicycle component of FIG. 1;

FIG. 4 is a top view of FIG. 3;

FIG. 5 is a bottom right side view of FIG. 1;

FIG. 6 is a right side view of FIG. 1;

FIG. 7 is a bottom left side view of FIG. 1;

FIG. 8 is a perspective view similar to FIG. 1, of one side of the cover sheath for a grippable bicycle component, mounted on a grippable support attaching a lever to a handlebar;

FIG. 9 is a perspective view of the other side of the cover sheath for a grippable bicycle component of FIG. 8;

FIG. 10 is a side view of the cover sheath for a grippable bicycle component of FIG. 8;

FIG. 11 is a top view of FIG. 10;

FIG. 12 is a bottom right side view of FIG. 8;

FIG. 13 is a right side view of FIG. 8; and,
